SURFACE ROD LINE JACK

William J. Jones, Oblong, Ill.

Application February 13, 1942, Serial No. 430,820

5 Claims. (Cl. 74—593)

This invention relates to well pumping apparatus and particularly to an improved surface rod line jack for providing a connection between the power source and the pumping mechanism.

An object of the invention is to provide a rod line jack which is safe and easy to operate and which at the same time is of relatively simple, yet rugged construction.

Another object is to provide a rod line jack which may be made in part of stock material readily available in the field.

A further object is to provide a rod line jack embodying a minimum number of parts which may be easily assembled and disassembled.

Other objects and advantages of the invention will become apparent in view of the following description taken in conjunction with the drawings, wherein:

Fig. 1 is a view in section and elevation of the rod line jack in accordance with the invention; and

Fig. 2 is a plan view thereof.

Referring to the drawing in detail, the improved surface rod line jack comprises a draw bar 10 formed with a series of ratchet teeth 11 along the length thereof. The draw bar 10 may be of any length necessary and at its inner extremity projects free to receive a power coupling member in the form of a pipe or tube 12 which is slidably telescoped over said extremity. A traveling latch head 13 is threaded or otherwise secured on the inner end of the coupling pipe 12, said latch head 13 being formed with an opening or slot 14 in which a traveling latch 15 is operatively mounted. The bar 10 is preferably rectangular in cross-section and freely engages a longitudinal rectangular opening in the head 13, to assure the alignment of the bar 10 in operation. The lower end of latch 15 is formed with a pawl 15' and the upper end of the latch is preferably of substantial length and provided with an enlargement defining a weight 15''. The latch is rotatably mounted on a bearing bolt 16 which is projected through the latch head and removably secured in place as by means of a cotter key 16'. To limit the rearward movement of the latch 15, a stop 17 is projected through the rear extremity of the latch head and also provides a rest for the latch 15 when the latter is in idle position. A lock member in the form of a key bolt 17' is slidably projected through the upper portion of the latch head 13 and serves to lock the latch back when desired.

The power end of the coupling tube or pipe 12 is pivotally connected to a member 18 mounted on a driving eccentric or cam 19 actuated from the main power source. The tube or pipe 12 may be of any length necessary and is shown provided with a coupling member 20 for connecting adjacent ends of pipe sections.

The coupling tube 12 is supported by a post 21 having on upper end thereof a slide bearing 22.

The draw bar 10 projects through the upper extremity of a supporting post 23, and removably secured to this latter post is a stationary latch block or head 24 having mounted therein a stationary latch 25 provided at its lower end with a pawl 25' and at its upper end with a weight 25''. The latch 25 is pivotally mounted on a removable pivot or bearing bolt 26 which may be removably held in place by a cotter key 26' or the like. A lock bolt 27 is slidably mounted in one side of the head 24 and may be used to lock the latch 25 back out of operative position when desired. Like the latch 15, the handle portion of latch 25 projects well upwardly for easy access without danger of the hands or fingers becoming engaged by pawl 25'.

The extreme outer end of the draw bar is shown connected to a rod line 28 by means of a clamp 29, the rod line being connected to pump-actuating mechanism generally indicated at 30 and which may be of any suitable type.

In operation, the draw bar 10 travels with the coupling pipe 12 during the normal stroke. When the well is hung up for any particular reason, the coupling pipe 12, latch head 13 and latch 15 travel over the draw bar, assuming the power source is still in operation and pumping other wells in the area. When it is desired to take up slack in the rod line connections, both the stationary latch 25 and traveling latch 15 are engaged with the teeth of the draw bar 10, the latch 15 sliding over the ratchet teeth of the draw bar on the return stroke of the tube 12 and engaging said teeth on the pull stroke, while the stationary latch prevents return movement of the draw bar. If for some reason the slack is to be let out, or the connections are to be lengthened, the stationary latch is disengaged until the stroke is almost out, whereupon the stationary latch is engaged and the traveling latch released until almost the limit of the pull stroke is reached, whereupon it is engaged and the stationary latch disengaged, and this process repeated until the tension is relieved from the rod line, whereupon both latches are disengaged and the draw bar is free and can be pulled out as far as desired.

When the well is pumping normally and the stationary latch is disengaged, the key 17 is pushed in to lock the said latch in idle position; and this may also be done with the latch 15 by manipulating the lock pin 17'.

Attention is directed to the fact that the latches 15 and 25 project straight upwardly well above the latch heads so that they are readily accessible for manipulation, while the lower or pawl extremities thereof are completely shielded against accidental contact with the fingers or

hands of an operator. Also the coupling pipe 12 completely shields the draw bar from the traveling latch rearwardly to the power connection. These are important features from a safety standpoint, since accidents oftentimes result in manipulating surface rod line jacks where the parts are exposed.

Simplicity of construction is another important factor as is also ease in operation. In this respect the one-piece latches 15 and 25 play an important part. The power coupling 12 may be made from stock available in the field and thus may be readily lengthened, repaired or replaced.

It will be understood that minor changes in construction and design may be made in my improved rod line jack without departing from the spirit or scope of the invention as defined by the appended claims.

What is claimed is:

1. In a surface rod line jack, a draw bar provided with a series of ratchet teeth along a surface thereof, the outer end of said draw bar being adapted for connection with a rod line and the inner extremity of said bar projecting free, an elongated tubular coupling member connecting the draw bar to a power source, said tubular coupling member enclosing a substantial portion of the draw bar and having a hollow latch head mounted on the inner end thereof, a traveling latch pivotally mounted in said latch head and provided with a pawl adapted for engagement with the teeth of the draw bar when the coupling member is given a power stroke, a support for the rod line, another latch head secured to said support, a stationary latch pivotally mounted in said latter latch head and provided with a pawl adapted to cooperate with said traveling latch under certain operating conditions, said latch heads having upwardly projecting portions shielding said pawls and adjacent lower portions of the latches.

2. In a surface rod line jack, a draw bar provided with a series of ratchet teeth along a surface thereof, the outer end of said draw bar being connected to a rod line and the inner extremity of said bar projecting free, an elongated coupling tube telescoped over the free extremity of the draw bar, a hollow latch head connected to the inner end of the tube and having upwardly projecting side portions providing a housing opening of material depth, a traveling latch having a pawl formed on its lower end disposed in said opening and pivotally connected to said latch head, said pawl being adapted to engage said teeth when a power stroke is applied to said coupling member, the pawl and lower portion of the latch being completely shielded by said latch head, an upright support through which said draw bar has movement, a latch head secured to said support and also having upwardly projecting housing portions on opposite sides of said draw bar, and a stationary latch having a pawl formed on its lower end adapted to engage the teeth of the draw bar to cooperate with said traveling latch under certain operating conditions, the pawl and adjacent lower portion of the stationary latch being also shielded by the said housing portions.

3. In a surface rod line jack, a draw bar provided with a series of ratchet teeth along a surface thereof, the outer end of said draw bar being connected to a rod line and the inner extremity of the draw bar projecting free, a coupling member telescoped over the free extremity of said draw bar, the outer end of said coupling member

being connected to a power source, a latch head connected to the inner end of said coupling member and having upwardly projecting housing portions on opposite sides of the draw bar, a traveling latch pivotally mounted in said latch head and having a pawl on its lower end adapted to engage the teeth of the draw bar when a power stroke is applied to the coupling member, said pawl and latch being of rigid construction and having a handle portion projecting upwardly a material distance over the latch head, means for limiting the throw-out movement of said latch, and a lock member mounted in one of the upwardly projecting side portions of said latch head and adapted to engage and hold the latch in throw-out position.

4. In a surface rod line jack, a draw bar provided with a series of ratchet teeth along a surface thereof, the outer end of said draw bar being connected to a rod line and the inner extremity of said draw bar projecting free, a coupling member telescoped over the free extremity of the draw bar and a latch head connected to the inner end of said coupling member, upright supports one through which said draw bar has movement and another providing a slideable bearing for said coupling member, a stationary latch head secured to said first-named support, both of said latch heads being provided with housing portions which project upwardly on opposite sides of the draw bar, a rigid one-piece traveling latch mounted in said first-named latch head and a similar latch mounted in said second-named latch head, each of said latches being provided with a pawl at its lower end adapted to engage the teeth of the draw bar under certain operating conditions, a stop for each of said latches for limiting the throw-out movement thereof, and lock pins slidably mounted in said housing portions and adapted to be projected into the path of the movement of the latches and lock the same in throw-out position.

5. In a surface rod line jack, a draw bar provided with a series of ratchet teeth along the top surface thereof, the outer end of said draw bar being connected to a rod line and the inner extremity of said draw bar projecting free, a hollow coupling member slidably telescoped over the free extremity of the draw bar, a latch head connected to the inner end of said coupling member, a pair of upright supports, one having an opening through which said draw bar has movement and the other of which provides a slideable bearing for said coupling member, a stationary latch head secured to said first-named support in substantially horizontal alignment with said opening, both of said latch heads being provided with housing portions which project upwardly on opposite sides of said draw bar, a rigid one-piece traveling latch mounted in said first-named latch head and a similar latch mounted in said second-named latch head, each of said latches being provided with a pawl at its lower end adapted to engage the teeth of the draw bar under certain operating conditions and a counter weighted handle portion projecting upwardly beyond the housing provided by its coacting latch head, a stop for each of said latches for limiting the throw-out movement thereof, and lock pins slidably mounted in said housing portions and adapted to be projected into the path of movement of the latches and lock the same in throw-out position.
